UNITED STATES PATENT OFFICE.

EDWARD W. McCARROLL, OF PITTSBURGH, PENNSYLVANIA.

DESIGN FOR A DOLL.

Application filed July 19, 1926. Serial No. 18,403. Term of patent 3½ years.

To all whom it may concern:

Be it known that I, EDWARD W. McCARROLL, a citizen of the United States, residing at Pittsburgh, Pennsylvania, have invented a new, original, and ornamental Design for Doll, of which the following is a specification, reference being had to the accompanying drawing, forming a part thereof.

The single figure of the drawing is a face view of a doll showing my new design.

I claim:

The ornamental design for a doll, as shown.

EDWARD W. McCARROLL.
